PREPARATION OF AROMATIC PETROLEUM CONCENTRATE OF REDUCED SULFUR CONTENT

Clinton H. Holder and Chester L. Read, Westfield, N.J., assignors to Esso Research and Engineering Company, a corporation of Delaware

Application December 21, 1954, Serial No. 476,776

1 Claim. (Cl. 208—96)

This invention relates to the preparation of condensed ring aromatic petroleum concentrates and particularly to the preparation of such concentrates which have a moderately low sulfur content, i.e., about 0.8% or less sulfur content by weight.

Condensed ring aromatic concentrates are particularly useful as a flux oil for coal tar burned as fuel in open hearth furnaces and the like. A highly aromatic material is particularly desirable for such applications in that the luminosity of the flame produced increases with aromatic content. Highly luminous flames are very desirable in reverberating furnaces or the like. In addition, such materials may be employed in making electrode coke for the aluminum industry and as intermediates in the manufacture of various chemicals such as acids derived from condensed ring aromatic compounds. They may also be used as heat exchange media. In the past the preparation of such materials from petroleum distillates has been made difficult due to the fact that the requirements of the steel and aluminum industries necessitate the production of material having a fairly low sulfur content. This is necessary to avoid absorption of sulfur by the metallic charge in the furnace. While numerous processes exist for the reduction of sulfur content in various petroleum distillates to a satisfactory level, most of these processes involve a hydrogenation reaction which converts the sulfur to hydrogen sulfide and at the same time results in the hydrogenation of the aromatic compounds. In addition, sulfur is very often associated with aromatic rings so that highly aromatic concentrates generally contain large amounts of sulfur. It has been possible, therefore, to produce an aromatic concentrate of low sulfur content only where the concentration of aromatics was relatively low.

It is an object of this invention to provide a process whereby a condensed ring aromatic concentrate derived from petroleum and having both a low sulfur content and a high concentration of aromatics may be produced.

It is a further object of this invention to provide a process whereby catalytically cracked cycle stock may be converted to a relatively low sulfur content aromatic concentrate without hydrogenation of the aromatic content thereof.

These and other objects, which will be in part apparent and in part specifically pointed out in the ensuing description, are attained by distilling a crude oil to produce a fraction boiling above about 600° F., subjecting this fraction to catalytic cracking, segregating the cracked products to form a fraction boiling in the same range as the original distillate, subjecting this cracked stock to a solvent extraction process in order to segregate aromatic compounds, and then contacting the aromatic concentrate produced by this extraction process with hydrogen in the presence of a catalyst in order to reduce the sulfur content of the concentrate.

It has been found that in order to produce a satisfactory aromatic concentrate it is necessary that the fraction

2

distilled from the crude oil be subjected to catalytic cracking. Prior to cracking the gas oil fraction normally contains less than 25% by weight of aromatics. This step is believed to cause the dehydrogenation of naphthenes so that the aromatics in the catalytically cracked cycle stock are in a form relatively easily separable by conventional solvent extraction processes such as extraction with phenol, liquid sulfur dioxide, or furfural. Most of the sulfur in the feed stock tends to concentrate itself in the aromatic phase so that the feed for the hydrodesulfurization step is of substantially higher sulfur content than the original crude. The hydrodesulfurization step of the process must be carried out under sufficiently severe conditions to materially reduce the sulfur content of the aromatic concentrate, but the reaction conditions must not be severe enough to cause hydrogenation of the condensed aromatic ring compounds therein. It has been found that these conditions are attainable when the hydrodesulfurization is carried out in the presence of a supported cobalt molybdate catalyst in the temperature range of about 600°—800° F., and preferably between 650° F. and 750° F.

A more complete understanding of the present invention may be had by reference to the accompanying single figure of drawings, which is a diagrammatic representation of a process embodying the present invention.

The drawing shows a conventional crude still 19 into which crude oil is introduced through line 11. Heavy residual products are removed from the bottom of the still at 12, while light fractions are taken off overhead through line 13. The present invention is concerned with the processing of that fraction boiling in the range of about 600° F. to about 1200° F. which is removed from the still through line 14 and passes to the catalytic cracking unit 15. In the catalytic cracking unit the feed stock is cracked under conditions well known to the art and forms a hydrocarbon mixture containing a substantial concentration of aromatic compounds. As previously stated, these aromatic compounds are particularly well adapted to solvent separation from the aliphatic constituents of the cracking stock and are peculiar to catalytic as opposed to thermal cracking. For this reason the cracking operation carried out in unit 15 must be of a catalytic nature. Any conventional catalytic cracking system adapted to convert hydrocarbons into materials of a lower boiling range may be employed. The process may be of a continuous or batch operation in fixed bed, moving bed, "fluid" or suspensoid systems. Heat required for cracking may be supplied as preheat of the distillate and/or as sensible heat of exothermically regenerated catalyst, or in any other conventional manner. Modified natural or synthetic clay or gel type catalysts such as silica-alumina composites or other conventional cracking catalysts may be employed at temperatures of about 800°—1000° F. and at pressures of from about atmospheric to about 25 p.s.i.g., all in a manner well known to the art.

The cracked cycle stock is passed from the cracker 15 via line 16 to the still 17. There the cracked hydrocarbon mixture is separated into a light fraction taken off overhead at 18, a heavy residual fraction taken off at 19, and a fraction boiling in approximately the same range as the feed stock for the catalytic cracking operation, namely, 600°—1200° F. This fraction, referred to as catalytically cracked cycle stock, is taken off via line 20 and passed to the extraction tower 21. For purposes of illustration it will be assumed that the extraction operation carried out in tower 21 utilizes phenol as a solvent for the aromatics in the feed stock. However, it is to be understood that phenol is specified only for the purpose of illustration and that other solvents exhibiting

similar selectivity for aromatics, such as liquid sulfur dioxide, nitrobenzene, aniline, cresol, and furfural, may be employed with equal facility. The phenol extracts the aromatic content of the catalytically cracked cycle stock in a manner well known to the art, forming an extract phase in which the aromatics are concentrated and a raffinate phase relatively poor in aromatics, which latter is taken off through line 22 and passed to a suitable solvent recovery system not shown. The extract containing the aromatics passes via line 23 to the stripper 10 24, wherein solvent is separated from the aromatic hydrocarbon concentrate, the solvent being removed overhead through line 25 while the aromatic concentrate is removed via line 26.

As pointed out above, the aromatics produced during catalytic cracking are particularly adapted to separation by solvent extraction. In addition to this, the operation of catalytic cracking itself increases the content of condensed ring aromatic compounds. A comparison is set forth below, illustrating the concentration by weight of compounds containing aromatic rings in various extraction cuts made by the phenol extraction of a typical cracked cycle stock and a typical virgin lube distillate. From this comparison it is seen that the concentration of aromatics is considerably greater for the same yield when extracting cycle stock than when extracting the virgin distillate.

	Catalytically Cracked Cycle Stock	Virgin Lube Distillate
Aromatics in Feed to Extraction, Wt. Percent	42	30-34
Aromatics in Extract, Wt. Percent:		
At 10% Extract Yield	98	87
At 20% Extract Yield	97	78
At 40% Extract Yield	85	66
At 60% Extract Yield	73	-----

The efficiency of the extraction process may be controlled by varying temperature, amount of solvent employed, etc. For example, at extraction temperatures of 125°-190° F. using phenol modified by 1-10% of water, the following relation exists between extract yield and amount of phenol employed.

Extract Yield, Percent	Percent Solvent on Feed by Volume
10	75
20	125
40	175
60	250

It will be appreciated from the above that extracts of sufficiently high aromatics concentration can be prepared using from about 75% to about 200% by volume of phenol based on feed.

The above comparison illustrates the advantages of using catalytically cracked cycle stock as a feed material to the hydrodesulfurization process and also that more highly concentrated aromatic feeds may be obtained when operating the extraction process at relatively low efficiency.

Although the concentrate leaving the stripper through line 26 is rich in condensed ring aromatics and therefore of potential value as a flux oil, etc., it may have a sulfur concentration as great as or greater than that of

the original crude oil. In order to prepare a concentrate suitable for use as flux oil or the like, it is necessary to effect a substantial reduction in the sulfur content of this aromatic extract, i.e., to reduce the sulfur content to a level not higher than about 0.8% by weight. It is well known in the petroleum refining art to reduce the sulfur content of various hydrocarbon fractions by contacting them with hydrogen under suitable conditions in order to convert the sulfur to hydrogen sulfide. In some cases the hydrogen is supplied by the dehydrogenation of various constituents of the hydrocarbon fraction. Such a hydrodesulfurization method is unsuitable for the treatment of highly aromatic stocks, however, and it has been found necessary to utilize a hydrodesulfurization step in which the hydrogen is supplied from an external source rather than by dehydrogenation of the hydrocarbon constituents being treated.

Accordingly, the hydrodesulfurization of the aromatic concentrate is carried out in reactor 27, into which hydrogen is introduced via line 28. The hydrogen and the aromatic concentrate must be contacted in the presence of a catalyst in order to produce the desired reaction. Numerous catalysts which will effect this result are known to the refining art, and any of these well-known methods may be employed in reactor 27 in accordance with the present invention. It has been found, however, that most beneficial results, from the standpoint of reducing sulfur content and of retaining a relatively high level of aromaticity, are obtained when a cobalt molybdate catalyst is employed. Catalysts made up of from 3-24% by weight of cobalt molybdate supported on Al_2O_3 , and preferably containing about 15% by weight of cobalt molybdate, are particularly suitable. Mixtures of cobalt and molybdenum oxides may be employed instead of cobalt molybdate. Other desulfurizing catalysts that may be employed include platinum (up to about 2%) supported on alumina and molybdenum oxide-alumina compositions. The contacting may be carried out utilizing a fixed bed technique, or in any other conventional manner.

In order to minimize or substantially prevent the hydrogenation of the aromatic compounds in the concentrate while the hydrodesulfurization reaction is taking place, it is necessary to carefully control the conditions existing within the hydrodesulfurization unit 27. In general, the hydrodesulfurization conditions must be kept relatively mild, that is, factors which would tend to cause hydrogenation of the aromatics must be maintained near their minimum limits. These factors are temperature, 45 pressure, and ratio of hydrogen to aromatic concentrate employed. A suitable temperature range has been found to be from about 600° F. to 800° F., and preferably from 650° F. to 750° F. Pressures in the hydrodesulfurization unit should be kept at about 50 to 500 p.s.i.g., with a preferred range of 300-500 p.s.i.g., and the gas rate from about 400 to about 4000 cubic feet of hydrogen per barrel of feed.

The concentrate is withdrawn from the hydrodesulfurization unit 27 via line 29. This concentrate, in addition to being useful as a flux oil for coal tar or other reverberatory furnace fuels, may also serve as a starting material for the manufacture of various condensed aromatic ring compounds. Specific aromatic compounds or types of compounds may be isolated from this stream and used for any desired purpose.

The hydrodesulfurization catalyst may become coated with carbon after an extended period of use. Such a deposit may be removed by a suitable oxidizing procedure, and the catalyst may then be regenerated according to any technique known to the prior art.

As a specific example of the operation of the process of the present invention, an aromatic concentrate having the following inspections obtained from phenol extraction of catalytically cracked cycle stock was employed as a starting material.

Gravity, ° API	—1.5
Viscosity at 100° F., S.S.U.	957.0
Viscosity at 210° F., S.S.U.	50.3
Sulfur, weight percent	1.83
Conradson carbon, weight percent	5.0
Tag Robinson color	1/4
Pour point, ° F.	45
Refractive index at 75° C.	1.6434
Aniline point, ° F.	—43
Aromatics by silica gel, wt. percent	92
Initial boiling point, ° F.	527

Using this feed stock, two hydrodesulfurization runs were carried out using a 15% cobalt molybdate catalyst supported on Al_2O_3 and externally supplied hydrogen. The conditions of these hydrodesulfurization runs are set forth in Table I below.

Table I

	Run 1	Run 2
Oil rate, volumes per volume of catalyst per hour	1.0	2.0
Temperature, °F	700	700
Total Gas Rate, Standard Cubic Feet per Barrel	3,500	3,500
Fresh Hydrogen Rate, Standard Cubic Feet per Barrel	1,000	1,000
Pressure, p.s.i.g.	400	400

In both cases the hydrofinned liquid was lemon yellow in color and had the following inspections set forth in Table II below.

Table II

	Run 1	Run 2
Gravity, ° API	1.2	0.8
Viscosity at 100° F. S.S.U.	597	
Viscosity at 210° F. S.S.U.	47.4	47.6
Sulfur, Weight Percent	0.5	0.8
Conradson Carbon, Weight Percent	3.0	3.1
Pour Point, ° F.	30	35
Refractive Index at 75° C.	1.6210	1.6241
Aniline Point, ° F.	—22	—22
Aromatics by Silica Gel, Weight Percent	92	90
Initial Boiling Point, ° F.	514	439

From the above data it will be seen that the aromatic content of the feed stock, which is expressed here in terms of the percentage of compounds containing an aromatic ring, was not lowered appreciably or at all under the conditions of hydrodesulfurization employed, while the sulfur content was reduced very substantially to an acceptable level in each of the runs. The low sulfur content aromatic concentrate thus produced is useful as a flux oil for the burning of coal tar in open hearth furnaces, as pointed out previously, and also as the starting material for the preparation of various forms of car-

bon such as coke for the aluminum industry and carbon black.

While the invention has been described in terms of a specific embodiment employing a particular solvent extraction method for concentrating the condensed ring aromatic compounds and a specific hydrodesulfurization method, it is to be understood that the invention is not limited to the utilization of these specific means, but that equivalent steps known to those skilled in the art may be substituted therefor. The scope of the invention is therefore not to be limited except by the appended claim. What is claimed is:

The process of preparing a condensed ring aromatic petroleum concentrate useful as a flux oil for burning coal tar in open hearth furnaces, said concentrate containing at least about 90 weight percent aromatic compounds and having a reduced sulfur content of less than about 0.8 weight percent, which comprises the steps of distilling a crude petroleum oil containing sulfur to form a gas oil fraction boiling above about 600° F. and containing at least about 1 weight percent sulfur, catalytically cracking said fraction to form a cracked hydrocarbon product, distilling said cracked hydrocarbon product to segregate a cracked fraction boiling above about 600° F., subjecting said cracked hydrocarbon fraction to a solvent extraction to produce an extract phase rich in aromatic compounds, recovering an aromatic hydrocarbon concentrate containing at least about 90 weight percent of aromatic hydrocarbons from said extract phase, and contacting said aromatic concentrate at a liquid oil space velocity rate of 1 to 2 volumes per volume of catalyst per hour with supported cobalt molybdate catalyst at 700° to 750° F. under a pressure of 200 to 400 p.s.i.g. in the presence of hydrogen gas flowing at a rate of 1000 to about 3500 standard cubic feet per barrel of the aromatic concentrate, said gas containing fresh free hydrogen supplied from an external source in an amount of at least about 1000 standard cubic feet per barrel of the aromatic concentrate treated to reduce the sulfur content of the thus treated aromatic concentrate to less than about 0.8 weight percent without appreciably lowering its aromatic content.
